UNITED STATES PATENT OFFICE.

WILLIAM RANCE, SR., OF FREEPORT, ILLINOIS.

DETACHABLE HANDLE FOR GRATE-SHAKER BARS.

Application filed May 29, 1925. Serial No. 33,791.

This invention relates to detachable handles for grate shaker bars.

The object is to provide means for locking extension handles to oscillating shaker bars in use on locomotives for the purpose of turning over the grate bars during the process of firing, the said means enabling the fireman to quickly and accurately apply the extension handle in position without the necessity for exercising any great care and automatically locking the same so as to avoid accidental disconnection, at the time of imparting the necessary force required to shake down the grate, especially while the locomotive is in motion.

Another object is to provide locking means for this purpose which is of simple construction, requiring but one additional part to act in conjunction with the means now in common use for connecting shaker handles to shaker bars, and requiring but a minimum amount of alteration in the members to properly adapt the same, the improved means serving at all times to automatically act when the handle is applied, and also permitting the latter to be freely removed from the shaker bar when the aforesaid part or member is moved slightly, either by hand or by the foot of the fireman, to unlock the members.

A full and complete understanding of the invention may be obtained from a consideration of the following detailed description, taken in connection with the accompanying drawing forming a part of this specification, it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claims.

In the drawing, in which similar reference characters designate corresponding parts throughout the several figures:

Figure 1 is a side elevation of a shaker handle applied to a shaker bar and held in engagement therewith by the improved locking means.

Figure 2 is an elevation of the same, taken at right angles to Figure 1, the upper portion of the handle being broken away.

Figure 3 is a vertical section, taken on the

line 3—3 of Figure 2 and looking in the direction of the arrows.

Figure 4 is a transverse section taken on the line 4—4 of Figure 3, and looking in the direction of the arrows.

The shaker bar 1, as shown in the drawing, is of the usual type employed on locomotives and in other places, said bar being in the form of a lever fulcrumed at an intermediate point, upon a pivot pin 2 generally carried by a bracket (not shown), or in any other desired manner, to locate the same in proper position relative to the grate bars to be rocked or shaken. The lower end of the shaker bar 1 is pivotally connected to a rod 3 which extends to the grate bars, and the upper end of the bar is extended upwardly a greater distance than the lower portion below the pivot, and is preferably tapered, as shown, and said upper end 4 is provided, on opposite faces, with transversely disposed flanges 5 to provide a shoulder on either side, to arrest the downward movement of the operating handle 6.

The flanges 5 are located at the proper position on the tapered, upper end of the bar 1 to contact with the lower end of the enlarged head 7 formed on the end of the handle 6, and to cause the tapered socket 8, formed in the head, to snugly fit the extended, upper end of the bar, and prevent any relative movement between the two members, and yet to avoid any frictional binding of the same, so that the handle may be freely withdrawn from engagement with the shaker bar.

The head 7 is shown as arranged to one side of the handle proper so that the tapered upper end of the shaker bar may lie flat against the side of said handle (see Fig. 2), the socket being so located in the head as to permit of same and, as will be seen by reference to Figures 1 and 3 of the drawing, the said head is also offset to one side of the longitudinal axis of the handle, while the socket is in longitudinal alinement with the same. This arrangement provides a thicker wall 7^a to one side of the socket and, midway between the upper and lower ends of the head, there is provided a transverse slot 9 extending entirely through said wall 7^a, said slot being arranged at an angle, the lower, inner end of the same intersecting the adjacent, inclined wall of the socket.

A locking pin, which may be in the form of a stout bolt 10, is loosely mounted in the

transverse, inclined slot of the head, said pin having terminal heads 11 to prevent the same from dislodgment from its seat in the slot, the heads, which may comprise the head 5 of a bolt and a nut, being spaced sufficiently from the sides of the socket as to permit the pin or bolt to slide up and down in the slot, in an obvious manner.

The free, tapered, upper end of the shaker 10 bar 1 is provided in one of its edges with a transverse, horizontally disposed groove 12 extending entirely across said face or edge, the said groove being slightly less than semi-circular in cross section and of a size to 15 fit the diameter of the bolt or pin 10, which is adapted to gravitate thereinto when the socket is fitted over the upper end of the shaker bar and lowered until the head of the handle rests upon the side flanges or 20 stops 5.

When the socket is introduced over the upper end of shaker bar, in applying the handle for use, the upper, adjacent corner of the tapered end of the bar encounters 25 the central portion of the locking pin, where the same extends into the socket at the lower end of the slot, and such contact forces the pin outwardly and upwardly along said slot sufficiently to allow the entrance of the 30 shaker bar. When the handle has been lowered to bring the transverse groove 12 in alignment with the lower end of the slot, the pin immediately falls or rolls into said groove and locks the head of the handle 35 upon the shaker bar when the operation of shaking the grate may be proceeded with and the violent movements imparted to the handle as well as the rocking and shaking movements of the moving locomotive, 40 will fail to dislodge the connection. When, however, it is desired to remove the handle which is always done after the shaking operation is completed, because of the restricted space in the cab of a locomotive, 45 it is only necessary to slide the pin or bolt 10 slightly up the inclined slot, when the handle may be easily and quickly removed and this freeing of the pin may be accomplished either by the hand or the foot of the 50 fireman.

From the foregoing it will be seen that

a simple means has been provided for securely locking together the handle and shaker bar of a locomotive or other similar members, and it should be noticed that existing members of this character may, by the mere addition of the inclined slot in the socket member of the shaker handle and the provision of the transverse groove in the proper face of the upper, free end of 60 the shaker bar, be altered to include the improved locking means, in which event the locking pin may be in the form of the bolt and nut, as stated.

What is claimed is:—

1. In combination with a grate shaker bar, a detachable handle comprising a handle lever; a one-piece socket member at the lower end thereof fitting the end of the shaker bar; shoulders on the bar abutting 70 the lower end of the socket member; said shaker bar having a groove in one face; said socket member having an inclined slot on one side extending transversely through the same, said slot being closed at its upper 75 end and extending at its lower end into the socket and being in alignment with the groove when the shoulders are engaged with the socket and being in alignment with the slot and engaging in the groove when 80 aligned therewith to lock the handle to the bar.

2. In combination with a grate shaker bar, a detachable handle comprising a handle lever; an open-ended socket member at one 85 end thereof fitting the end of the shaker bar, said socket member having a transverse, inclined slot at one side thereof and extending at its lower end into the socket; opposite shoulders on the bar abutting the lower 90 end of the socket member; said bar having a transverse groove aligned with the lower end of the inclined slot when the shoulders are engaged with the socket member; and a bolt loosely mounted in the slot and partially entering the groove in the bar to prevent removal of the handle from the 95 bar.

In testimony that I claim the foregoing as my own, I have hereto affixed my signature.

WILLIAM RANCE, Sr.
